1

This invention relates to multiple rotary cutter wood slotting machines of the kind wherein the cutters are movable longitudinally of the wood stock to form longitudinal slots therein.

The object of the present invention is to provide, in such machines, means for coupling a number of cutters together for simultaneous longitudinal movement by hand, the total amplitude of movement by each cutter being variable within limits and variable with respect to the amplitude of movement of each of the other cutters.

According to the present invention such means comprise a plate, provided with a series of parallel guides, pivoted to a fixed part of the slotting machine and rotatable about an axis lying in a plane parallel to that of the wood stock and at right-angles to the longitudinal axis of the slots to be cut, the guides of the plate being at right-angles to the axis of rotation of the plate, anchor members engaged one with each guide of the plate and adjustable and securable in a desired position along the length of the respective guide so as to permit variation of the length of arc traversed by each anchor member as the plate is rotated, and connection links coupled one between each anchor member and one of the cutters, whereby when the plate is moved through a portion of a revolution the respective cutters are moved longitudinally of the wood stock for a distance determined by the relative positioning of the corresponding anchor member on its guide of the plate.

An embodiment of the present invention is shown in accompanying drawing, wherein:

Figure 1 shows the guide plate seen in front view; Fig. 2 shows the guide plate in side elevation; Figs. 3 and 4 are respectively a schematic side elevation and a schematic plan view of a cutter to which an embodiment of the invention is applied; Fig. 5 illustrates diagrammatically the principle of operation of the apparatus.

The movable plate 1 (Figure 1) is constituted by a preferably metallic member of rectangular shape in which are provided grooves or slideways such as 2, 3, 4.

These slideways are provided with graduations such as 5, 6.

At the lower part 7 of the plate 1 are disposed bearings 8, 9 supporting pivotal shafts 10 (Fig. 2). Control rods 11 are each coupled to the plate by an articulated link arm 12, ball and socket joints 13 and 14, and an anchor bolt 15 constituted by a head 16, a threaded portion 17 and a locking nut 17*.

The plate 1 is mounted on the frame 18 of 55

the machine by means of the shafts 10 and stops 19 limit the amplitude of movement of rotation of the plate to 180°.

The upper part 20 of the slotting machine comprises guiding rails 21 on which move supports 22 with trackways 22* for the motors 29 driving the cutters 30 and 31. The motors 29 are secured in position on the carriage supports 22 by conventional tightening means (not shown).

10 The control rods 11 are supported by the bearings 25 and 26 of the frame 18 and pass through the carriage supports 22 of the motors. Keying means 27, 28 permit to couple the rods 11 to the corresponding carriage supports 22.

15 The operation is as follows:

Each cutter assembly comprises a motor 29 and the slotting cutter 30, or 31. The machine comprises a number of cutters corresponding to the number of slots to be made on the piece 32 to be worked.

20 The carriage supports 22, movable in the direction of the arrows A, B on the rails 21, are bored to receive the parallel rods 11.

The motors 29 for driving the slotting cutters 25 are movable in the direction of the arrows C, D.

The left-hand extremities of the rods (in Figs. 2, 3, 4 and 5) are each coupled to the plate in the manner described with reference to Fig. 2.

25 The operator has only to dispose the carriage supports 22 on the rails 21 at predetermined positions where the slots are to be effected on the piece of wood.

The work piece would conveniently be fixed on a table (not shown) which would be arranged to slide vertically by known means.

30 If the cutter 30 has to effect a slot of two centimeters length and the cutter 31 a slot of four centimeters length, the rod 24 is fixed to one carriage support 22 (Fig. 4) and the rod 23 to the other carriage support by the keying means 27 and 28.

35 The anchor bolt of each rod is then positioned at the appropriate graduations 5 and 6 and the plate (Fig. 5) is thereafter rotated through 180° to effect longitudinal movement of the cutters.

40 The movement of the plate will move the rod 23 by a distance E, F whilst, by the same movement, the rod 24 will be displaced by a distance G, H.

45 The cutter coupled to the rod 23 will be displaced by a similar amplitude I, J, whilst the cutter coupled to the rod 24 will effect a simultaneous movement of an amplitude K, L equal to that of G, H.

The positioning of the slots in the direction

transverse to their length is obtained by transverse displacement of the cutter motors on their carriage supports.

The plate comprises as many slots as the machine has cutters.

I claim:

1. In a multiple rotary cutter wood slotting machine, of the kind wherein the cutters are movable longitudinally of the wood stock to form longitudinal slots therein, means for coupling a number of cutters together for simultaneous longitudinal movement, by hand, the total amplitude of movement by each cutter being variable within limits and variable with respect to the amplitude of movement of each of the other cutters, comprising a plate provided with a series of parallel guides, pivoted to a fixed part of the slotting machine and rotatable about an axis lying in a plane parallel to that of the wood stock and at right angles to the longitudinal axis of the slots to be cut, the guides of the plate being at right angles to the axis of rotation of the plate, anchor members engaged one with each guide of the plate and adjustable and securable in a desired position along the length of the respective guide so as to permit variation of the length of arc traversed by each anchor member as the plate is rotated, and connection links coupled one between each anchor member and one of the cutters, whereby when the plate is moved through a portion of a revolution the respective cutters are moved longitudinally of the wood stock for a distance determined by the relative positioning of the corresponding anchor member on its guide of the plate.

2. In a multiple rotary cutter wood slotting machine of the kind having a frame on which cutters are movable longitudinally of the wood stock to form longitudinal slots therein, means for coupling a number of cutters together for simultaneous longitudinal movement by hand, the total amplitude of movement by each cutter being variable within limits and variable with respect to the amplitude of movement of each of the other cutters, comprising a slotted plate pivoted to a fixed part of the frame of the slotting machine and rotatable about an axis lying in a plane parallel to that of the wood stock and at right angles to the longitudinal axis of the slots to be cut, the slots of the plate being at right angles to the axis of rotation of the plate, anchor bolts engaged one in each slot of the plate and adjustable and securable in a desired position along the length of the respective slot of the plate so as to permit variation of the length of arc traversed by each anchor bolt as the plate

is rotated, longitudinally slideable rods carried by the frame and coupled one to each cutter, and linking means connecting each rod with one of the anchor bolts, whereby when the plate is moved through a portion of a revolution the respective cutters are each moved longitudinally of the wood stock for a distance determined by the relative positioning of the corresponding anchor bolt in its slot of the plate.

3. In a multiple rotary cutter wood slotting machine of the kind having a frame on which cutters are movable longitudinally of the wood stock to form longitudinal slots therein, means for coupling a number of cutters together for simultaneous longitudinal movement by hand, the total amplitude of movement by each cutter being variable within limits and variable with respect to the amplitude of movement of each of the other cutters, comprising a slotted plate pivoted to a fixed part of the frame of the slotting machine and rotatable about an axis lying in a plane parallel to that of the wood stock and at right angles to the longitudinal axis of the slots to be cut, the slots of the plate being at right angles to the axis of rotation of the plate, stops secured on the frame adjacent the pivoted plate for limiting the movement of the plate to 180°, anchor bolts engaged one in each slot of the plate and adjustable and securable in a desired position along the length of the respective slot of the plate so as to permit of variation of the length of arc traversed by each anchor bolt as the plate is rotated, longitudinally slideable rods carried by the frame and coupled one to each cutter, universal joints provided on each anchor bolt and rod, and links coupled by said universal joints between each anchor bolt and the corresponding rod, whereby when the plate is pivoted through 180° the respective cutters are each moved longitudinally through a distance determined by the relative positioning of the corresponding anchor bolt in its slot of the plate.

GASTON BOREL.
